UNITED STATES PATENT OFFICE

GEORGE E. PICKUP, OF NEWARK, OHIO, ASSIGNOR TO THE WEHRLE COMPANY, OF
NEWARK, OHIO, A CORPORATION OF OHIO

DESIGN FOR A WARMING CLOSET FOR COOK STOVES

Application filed May 9, 1931. Serial No. 39,788. Term of patent 7 years.

To all whom it may concern:

Be it known that I, GEORGE E. PICKUP, a citizen of the United States, residing at Newark, in the county of Licking and State of Ohio, have invented a new, original, and ornamental Design for a Warming Closet for Cook Stoves, of which the following is a specification, reference being had to the accompanying drawing, forming part hereof.

The figure is a perspective view of a warming closet for a cook stove, showing my new design.

The design is especially characterized by the provision of a deep central compartment and two relatively shallow compartments on either side of the central compartment, with front closures for each of the compartments, substantially as shown.

I claim:

The ornamental design for a warming closet for cook stoves, substantially as shown and described.

GEORGE E. PICKUP.
